UNITED STATES PATENT OFFICE

2,644,399

GRENADE ALL-WAYS FUZE

Dallas C. Knowlton, Arlington, Va.

Application September 29, 1949, Serial No. 118,661

1 Claim. (Cl. 102—81.6)

(Granted under Title 35, U. S. Code (1952),
sec. 266)

1

The invention described herein may be manufactured and used by or for the Government for governmental purposes without the payment of any royalty thereon.

This invention relates to a grenade fuze and more specifically to a very simple and practical "all-ways" impact type fuze for use in hand grenades and the like.

An object of the invention is to provide a grenade or the like with a fuze that will function upon impact regardless of the angle that the grenade makes with the target upon impact.

Another object of the invention is to produce an "all-ways" fuze that is economical of manufacture and positive in action.

Another object of the invention is to produce an "all-ways" fuze that is easily assembled without requiring the use of special tools or skilled labor.

A practical embodiment of the invention is illustrated in the accompanying drawings wherein:

Figure 1 shows for the purpose of illustration a spherically shaped grenade in which is incorporated my "all-ways" fuze.

Figure 2 is a section taken along line 2—2 of Figure 1.

Figure 3 is a section taken along the line 3—3 of Figure 2.

Figure 4 is a perspective showing the sliding elements of the fuze.

Referring now to the drawings by characters of reference there is shown in Figure 1 an embodiment of my invention wherein 1 generally indicates the hollow body of a spherically shaped grenade having a filling hole plug closure 2 and a diametrically opposed threaded opening 4 for the purpose of receiving the "all-ways" fuze. Seated on an annulus 5 and retained in position by means of an externally threaded ring 6 is a substantially funnel shaped partition 7 holding a booster charge 8 in alignment with a detonator 9 and primer 10. The partition projects inwardly into the body of the grenade and is substantially surrounded by an explosive charge 11 contained in said body. The fuze housing assembly comprises two substantially dish shaped members 12 and 13 in threaded engagement as at 14 and forming a chamber 15 having a vertical wall 15a and inclined walls 16 and 17. A detonator charge 9 is fixed in a downwardly depending cylindrical extension 12a of the member 12. Resiliently supported within the chamber and normally between its vertical walls are two substantially rectangular shaped slide members 18 and 19 carrying a primer 10 and a firing pin 25 is opposed relation-

2

ship. The ends of the slide members adjacent to the vertical walls are provided with hemispherical bearing projections 20 to reduce friction. Slide member 19 is slotted as at 22 and 23 forming two arms 29. Positioned parallel to each arm in the slot 22 and each having one end fixed in the bottom of slot 22 are springs 24. Intermediate springs 24 in the bottom of slot 22 is fixed a firing pin 25. Slide member 18 is provided with a table 26 slidable in slot 22 and arranged to engage the springs 24 as at 27. Projecting downwardly from the table 26 is a guide 28 slidable between the arms 29—29 formed by the slots 22 and 23. The detonator 10 is housed in slide 18 in axial alignment with the firing pin 25 and intermediate the springs 24. Aligned ports 30 and 31 in the slide 18 and disk member 12 respectively provide communication between the primer and detonator.

20 A spring loaded cap 32 is pivoted to the base of member 13 as shown by the reference character 33 and is releasably held to the base by means of a cotter pin engaging a projection of said cap and a lug of the member 13 as generally indicated at 34. A spring 35 fixed to the inside of the cap and in engagement with the base of member 13 and throws the cap off the grenade. A string 36 is wound upon a spool 37 has one end fastened to the safety pin 38 as at 42 and the other end fastened to the cap as at 41. The safety pin passes through aperture 39 in the base of member 13 and into an aperture 40 in the slide member 18, holding the slide members in spaced relationship. Gaskets 12a and 13a form waterproofing means between the grenade body and fuze assembly, and the cap and fuze assembly respectively.

40 In throwing the grenade, the fingers of one hand are held over the pivoted cap and the cotter pin is removed by the other hand. As the grenade leaves the hand of the thrower the spring loaded cap is thrown from the grenade. The cap in flight will unwind the string from the spool and pull the safety pin out of the grenade at a safe distance from the thrower, leaving the grenade in an armed condition. In the armed condition the slide members containing the primer and firing pin are resiliently spaced by means of the springs. When the grenade strikes the target the slide members compress the springs and impinge the firing pin on the primer causing the detonator, booster and main charge to fire. It is apparent from the drawings that impact along the vertical axis will cause the two slide members 50 to slide along the inclined walls 16 or 17 and

laterally move toward each other overcoming the resistance offered by the springs and firing the primer. Impact in a direction at right angles to the vertical axis will cause the slide members to move only towards each other and fire the primer. Impact at any angle between the aforementioned limits will result in the slides moving along the inclined surfaces and towards each other causing the primer to function.

I claim:

In a fuze adapted to fit a grenade, a hollow body having upper and lower members threadedly engaged and forming a chamber for housing resiliently telescopically engaged firing elements, said chamber having vertical walls intermediate inwardly directed walls, said firing elements being substantially rectangular in shape and having their outer ends conforming to the contours of said chamber, one of said firing elements being slotted laterally and vertically to form two pairs of U-shaped legs, a firing pin fixed in the bottom of said lateral slot intermediate said pairs of legs, a spring fixed at one end within the confines of each pair of legs and each having its free end arranged to engage the other of said firing ele-

ments, the other of said firing elements being substantially longitudinally T-shaped in cross section to slidably engage the walls of said lateral and vertical slots, the inner end of said cross section engaging said springs resiliently spacing said firing elements to slidably engage the walls of said chamber, each of said firing elements being provided with hemispherical projections at their outer ends to engage the walls of said chamber, the vertical element of said cross section housing a primer in axial alignment with said firing pin and in communication with a detonator in said lower body member.

DALLAS C. KNOWLTON.
